ELECTRICAL MACHINERY BRUSH HOLDER
Neal A. Millar, La Grange Park, Ill., assignor to General
Motors Corporation, Detroit, Mich., a corporation of
Delaware

Filed Nov. 14, 1960, Ser. No. 68,731
3 Claims. (Cl. 310—246)

This invention relates generally to a structure associated with the brushes of electric motors and generators and more particularly to means for holding one or more brushes in contact with a commutator.

In designing a brush holder for the brushes of electrical machinery there are several factors which must be considered. First, a simple but effective means must be provided to engage the brush held by the brush holder and press the brush against its associated commutator. As the brushes wear, this brush engaging means must maintain the brush in contact with the commutator and it is desirable that the pressure applied to the brush by such means be non-variable irrespective of brush length.

Since these brushes are replaced from time to time as they wear out, the means normally holding the brushes in contact with the commutator must be capable of being retracted so that the old brush can be removed and a new one inserted. Brush engaging means previously available have not been made to be easily retractable. Furthermore, such prior constructions have required that the service personnel hold the brush engaging means in the retracted position with one hand while removing and replacing the brushes with the other hand. The above procedure is awkward because when the removal and replacement of brushes requires both hands of the person servicing the electric machine he has great difficulty holding the brush engaging means in a retracted position while replacing the brushes. Naturally, the stiffer the springs holding the brushes in contact with the commutator, the more awkward and difficult changing the brushes becomes. The present invention provides novel means for holding the brush holding means retracted to thereby facilitate removal and replacement of brushes.

In prior brush engaging construction, the fingers which were biased by the springs against the brushes to hold them in contact with the commutator were commonly pivoted at one end, usually by means of a rivet, pin or the equivalent. Such construction, however, resulted in considerable rivet or pin and spring breakage. While such rivets are still used, the present construction additionally provides for sliding movement of the pivoted ends of the fingers. This sliding movement allows the springs to locate the fingers so that the brush spring functions normally and without restriction. The sliding arrangement also allows shock and vibrating loads applied to the motor armature to produce a slight sliding action instead of an impact action as was produced when the ends of the fingers were pivotally anchored by rivets, etc. It has been found that this sliding feature practically eliminates rivet and spring failures.

Because of operational and functional difficulties which sometimes occur in electrical machinery of the kind concerned with here, there is always the possibility that so-called flashovers (arcing) may occur in the vicinity of the brush holders. It is important that the functioning parts associated with the brush holder such as the means holding the brushes against the commutator be protected from these flashovers or arcing so that they continue to be operable after a flashover occurs. The present invention includes as an important part thereof a case which encloses the main functioning part of the means which holds the brushes against the commutator, i.e., the spring. In tests carried out utilizing the brush engaging means,

2

it has been found that after severe flashovers there was no damage to the spring or other parts of the brush engaging means.

Another feature which is deemed worthy of special emphasis so far as the present invention is concerned is the utilization of split brushes in combination with means individually biasing each brush wafer against the commutator. This latter feature has the advantage of providing positive contact at all times of each brush wafer with the commutator thereby eliminating erratic commutation and reducing or eliminating commutator maintenance.

It is an object of this invention to provide means associated with an electrical brush holder which will hold the brushes against a commutator with constant non-variable pressure regardless of brush length.

It is a further object of this invention to provide means for locking the brush engaging means in a retracted position to facilitate the removal and replacement of commutator brushes.

It is a further object of the invention to provide a unique pivotal means in which the brush engaging means is slidably when retracted to engage in a detent against which it is yieldably held by the spring also acting to apply the pressure to the brushes.

For a fuller understanding of the above and other objects of this invention, reference may be made to the accompanying detailed description and the drawings in which:

30 FIGURE 1 is a view in elevation with certain parts in section of a brush holder including the brush holder stud mounting the brush holder on an electrical machine and with the means for holding the brushes against the commutator shown in the retracted position.

35 FIGURE 2 is a view similar to FIGURE 1 except that the brush engaging fingers are shown holding the brushes against the commutator.

FIGURE 3 is a top view of the brush holder including the brush engaging means.

FIGURE 4 is a sectional view taken substantially on the line 4—4 of FIGURE 2 illustrating details of the novel sliding pivot means for the brush engaging fingers.

FIGURE 5 is a view taken substantially on the line 5—5 of FIGURE 2 showing details of the constant pressure springs which serve to bias the brush engaging fingers thereagainst and which also serve to yieldably hold the fingers in their retracted position when it is desired to change out the brushes.

FIGURE 6 is an end view of an electric motor showing how the brush holders are mounted on the motor frame and the brushes engage the commutator of the motor.

Referring first to FIGURE 6, there is shown an electric motor indicated generally by the numeral 2 which includes a frame 4. Mounted for rotation within the frame 4 is the motor armature which includes its commutator 6. Mounted at circumferential locations about the armature 6 are four brush holders each indicated by the numeral 8. These brush holders 8 are secured to the motor frame 4 by insulating brush holder studs 10.

Referring now to FIGURES 1, 2 and 3 it will be observed that each brush holder 8 has provided at one end thereof an opening 12 for mounting it on its brush holder stud 10. At its opposite end there is provided a slot 14 in which is slidably mounted a split brush consisting of two wafers each indicated by a numeral 16. The brush wafers 16 as noted in FIGURES 1 and 2 engage and make electrical contact with the commutator 6 at their ends 18. The opposite ends of wafers 16 have electrically secured thereto the usual shunt leads 20 in turn secured at their opposite ends to a common terminal (see particularly FIGURE 3).

Mounted on each brush holder 8 is a brush holder spring cell which is indicated generally by a numeral 22. This cell 22 may be secured to the brush holder in any suitable manner. In the present instance it may be done by passing a bolt, stud or spindle 23 through the rivet 50 and the brush holder. The cell 22 includes a frame or case 24 having a base 26, opposite sides 28 and 30, and a longitudinally extending detent tab 32 forming an extension of the base 26. Mounted side by side between the opposite sides 28 and 30 of case 24 on rollers or spools 34 are a pair of non-cumulative force springs 36 which resemble rolls of metal tape wound on spools 34. This is the force utilized to hold the brush wafers 16 against the commutator and is of the same magnitude regardless of extended length as long as there is at least one turn of the coil remaining on the spools 34. The outside ends 38 of each spring 36 are riveted to a brush engaging finger 40 intermediate the ends of the associated finger. Each finger 40 is provided with a brush engaging portion 42 at one end thereof and a straight portion 44 which is pivotally but slidably anchored in a pivoting assembly 46. Each pivoting assembly 46 includes two blocks 48 which are pivotally secured side by side between the sides 28 and 30 by a rivet 50. Each block 48 is provided with a guide track 52 in which an end 44 of the associated finger 40 is longitudinally slidable.

The operation of the brush engaging means is as follows:

Referring to FIG. 2, it will be observed that the spring 36 by reason of its tendency to wind on the roller or spool 34 causes the finger 40, including the brush engaging portion 42, to engage the outer ends of the brush wafers 16 thereby holding them against the commutator 6. Because of the characteristic of the spring 36 which exerts the same bias irrespective of how far it is rolled on the spool 34, equal forces are applied to the brush wafers 16 and consequently, equal pressures to the commutator 6 regardless of brush wear.

If it is desired to change out the brush formed by wafers 16, each finger 40 may be individually retracted by pulling back on its brush engaging end 42 so that the end 44 of finger 40 slides in its guide 52 until it engages the detent 32 against which it will be yieldably held by the tension in spring 36. These fingers 40 are shown in their retracted position in FIGURE 1. After the brush has been removed and replaced, the fingers may again be moved to their operative position against the outer ends of the brush wafers by simply pulling outwardly on the brush engaging portions 42 so that the end 44 no longer engages in the detent 32.

From the foregoing description, it may be appreciated that a simple but extremely effective brush holder spring cell has been provided which is easily adaptable to many brush holders for electrical machinery. It also has the desirable feature of providing constant and uniform pressure to hold the brushes against the commutator. As previously emphasized, the brush engaging fingers are easily retractable to a locked position to facilitate changing out of the motor brushes.

I claim:

1. Cellular means for holding a brush in contact with a commutator comprising a supporting case, a brush engaging finger mounted in said case and having a free brush engaging portion extending therefrom, a spring secured to said finger and to said case adapted to cause said finger to exert a non-variable pressure on the brush it is adapted to contact when said case is secured in juxtaposed relation thereto, and means to lock said finger in a retracted position in order to remove and replace the brush normally engaged thereby including guide means slidably guiding said finger and pivotally secured to said case and a detent on the opposite side of the point of pivotal connection of said guide means to said case from said brush engaging portion to which an end of said finger is movable and against which said end is yieldably held by said spring when said finger is retracted.

2. Cellular means for holding a brush in contact with a commutator comprising a supporting case, a brush engaging finger mounted in said case and having a free brush engaging portion extending therefrom, a spring whose bias is the same irrespective of its deflection secured to said finger and to said case adapted to cause said finger to exert a constant pressure on the brush it is adapted to contact when said case is secured in juxtaposed relation thereto, and means to lock said finger in a retracted position in order to remove and replace the brush normally engaged thereby including guide means slidably guiding said finger and pivotally secured to said case, and a detent on the opposite side of the point of pivotal connection of said guide means to said case from said brush engaging portion to which an end of said finger is movable and against which said end is yieldably held by said spring when said finger is retracted.

3. In combination with an electrical machine having a commutator, a brush holder mounted adjacent said commutator, a brush mounted in said brush holder and engaging said commutator, means for holding said brush in contact with said commutator comprising a brush engaging finger having a free brush engaging portion extending therefrom, a guide for said finger slidably supporting said finger intermediate the ends thereof, and a spring adapted to bias said finger to cause said finger to exert a constant pressure on said brush, said finger being retractable against the bias of said spring, and means to lock said finger in a retracted position including a detent to which the end of said finger opposite said free brush engaging portion may be retracted and against which said end is yieldably held by said spring when said finger is retracted.
